UNITED STATES PATENT OFFICE.

HERBERT L. BRIGHT, OF NEW YORK, N. Y.

TYPE-WRITER ATTACHMENT.

1,245,144.

Specification of Letters Patent.

Patented Oct. 30, 1917.

Application filed January 4, 1916. Serial No. 70,287.

To all whom it may concern:

Be it known that I, HERBERT L. BRIGHT, a citizen of the United States, residing at New York, in the county of New York 5 and State of New York, have invented new and useful Improvements in Type-Writer Attachments, of which the following is a specification.

This invention relates to typewriting machines and particularly to an attachment therefor.

An object of the invention resides in the provision of means for minimizing eye strain incident to the common necessity of shifting the eye from the key-board to the platen or cylinder when the operator wishes to observe or verify the writing as it is placed upon the sheet. In view of this purpose of the invention, I have devised a system of 15 mirrors correlated whereby the image of the writing or matter as it is placed upon the sheet may be exhibited prominently from the machine at a point in a common line of vision with the key-board, and 20 through certain peculiarities of construction it is found practical to cause the image of the writing to appear in a magnified or intensified state in order that it will be properly visible to the eye of the operator.

Another object of the invention resides in the provision of an attachment of this character which will consist of a system of mirrors which are adapted to be individually adjusted whereby they may be made to 35 properly accommodate themselves respectively to the platen or cylinder and the key-board.

Another object of the invention relates to a structure of this character which will 40 include means whereby that mirror which is normally associated with the cylinder to receive reflections of the writing, may be conveniently adjusted away from the cylinder in order that the operator may freely manipulate the writing sheet as the occasion 45 may demand.

In the drawings forming a part of this specification and in which like reference numerals indicate similar parts throughout the 50 several views:—

Figure 1 is an end elevation of a type-writing machine showing the application of the invention thereto.

Fig. 2 is a side view of the attachment 55 removed from the machine.

Fig. 3 is a transverse section through the lower mirror.

Fig. 4 is a perspective view of one of the rocking studs.

The invention is used in the present instance in combination with what is known as an Underwood typewriter. In carrying the invention into practice, a tilting frame 1 is employed and it is preferred to mount the same upon suitable portions of the main frame of the typewriter. Vertical supports or props 2—2 rise from the frame of the typewriter and as illustrated, they are provided at their upper ends with angular alined extensions 3 in which circular studs 70 or pintles 4, are mounted to rock. These studs are provided with sockets or guide passages 4' and 5. The rocking or tilting frame 1 consists of sections 6 and 7, the former having parallel side arms 8—8 which 75 are freely slidable in the guide passages 4'. The mentioned arms may be securely confined against sliding movement by set screws 9 carried by the studs or pintles 4. The frame section 7 consists of similar parallel 80 arms 10—10 which are freely slidable in the passages 5 and they may be secured against sliding movement by set screws or the like 11.

As stated, hereinbefore, I have employed 85 a system of mirrors which may be associated, respectively with the platen or cylinder and the key board so that an image of the writing as it is projected into one mirror may be displayed and observed from 90 a common line of vision with the key board of the machine. In order that best results may be obtained, it is desirable to employ mirrors 12 and 13 which are arranged one above the other, the former being mounted 95 for tilting movements upon angular extensions 14 of swinging sections 15 of the frame section 6. The mentioned sections 15 are pivoted at 16 to the upper extremities of the arms 8—8 and incident thereto it 100 follows that the mirrors 12 may be expeditiously adjusted to and from the platen or cylinder at the convenience of the operator. By mounting the mirror 12 for tilting movements, it may be extended at the 105 proper angle to the platen or cylinder whereby to cause the writing upon the sheet to be properly reflected into said mirror and centered so that it may be projected and the image thereof correspondingly displayed 110 from the lower mirror 13.

The lower mirror is mounted at 17 for tilting movements from horizontal angular extensions 18 of the arms 10 forming the

frame section 7 of the tilting frame. It will be observed that this mirror can also be individually adjusted whereby to permit of its being operatively related to the upper mirror 12. At this point it is deemed advisable to mention that the reflecting surface of the mirror 12 is on the under side of the mirror body and that the mirrored surface of the mirror 13 is on the upper side. The mirror 13 is provided with a transversely convex display surface 19 and incident to this rather irregular or distorted condition of the mirror, the image of the writing will be exaggerated or suitably enlarged to permit of its being readily observed without straining the eyes of the operator. The frame 1 may be extended whereby to cause the mirrors 12 and 13 to be disposed at such selected points relatively of the platen or cylinder and the key board of the machine as may be found suitable to the taste of the operator. The mirror 13 is disposed directly above the key board and in a common line of vision therewith so that the image of the matter or writing to be exhibited may be observed without the operator having to change his eye from a fixed point upon the key board.

The pintles 4 are slidable in a horizontal direction in the extension 3 whereby the supports 2-2 may be made to operatively accommodate themselves to the sides of the typewriter frame. These studs may be held against movement in said extensions by means of set screws 3^a.

What is claimed as new is:—

1. The combination in a typewriting machine, of relatively adjustable mirrors, one of which being disposed in relation to the cylinder whereby the writing will be reflected thereon, the other mirror being adapted to receive the writing reflections from the first mirror and to visually display the same from the key-board.

2. The combination with a typewriting machine, of an observation mirror located in a common line of vision with the key-board and a second mirror located adjacent to the cylinder whereby the writing will be reflected thereon, and means for adjusting said mirrors to cause the reflected writing upon the second mirror to be displayed from the observation mirror.

3. The combination in a typewriting machine, of an observation mirror located in a common line of vision with the keyboard, and a second mirror located adjacent to the cylinder whereby the writing from the cylinder will be displayed upon the said second mirror and reflected therefrom upon the observation mirror.

4. The combination with a typewriting machine, of a longitudinally disposed tilt-

ing frame carried thereby and swinging mirrors upon the frame and arranged whereby the writing from the cylinder of the machine will be reflected upon one of the mirrors and reflected therefrom to the other mirror to visually display the same from the keyboard.

5. The combination in a typewriting machine, of a tilting frame carried thereby, said frame comprising two independent sections, means for adjusting either of said sections with relation to the other section, a swinging mirror upon one of the frame sections located in a common line of vision with the keyboard, swinging members connected with the other frame section, and a mirror pivotally secured to said swinging section, and located adjacent to the cylinder of the machine whereby to receive the written reflections from the first mentioned mirror and to convey the same to the operator of the machine.

6. The combination with a typewriting machine, of vertical supports rising from the frame of the machine, laterally disposed longitudinally adjustable rocking studs for the supports, a frame upon the rocking studs, said frame comprising two independent sections, means for adjusting either of the sections upon the studs, and a swinging mirror carried by each of the frame sections, one of said mirrors being located in a common line of vision with the keyboard and the second mirror located adjacent to the cylinder whereby the writing from the cylinder will be displayed upon said second mirror and reflected therefrom upon the first mentioned mirror, as and for the purpose set forth.

7. The combination in a typewriting machine, of the keyboard and a support carrying reading matter remotely located relative to the keyboard and an optical system comprising two reflectors so located as to visualize an image of one of the two mentioned objects in the general direction of the other.

8. The combination in a typewriting machine, of the keyboard and a support carrying reading matter remotely located relative to the keyboard, an optical system comprising two reflectors, a frame for supporting the reflectors and means for adjusting the reflectors to visualize an image of one of the two first mentioned objects in the general direction of the other.

In testimony whereof I affix my signature in presence of two witnesses.

HERBERT L. BRIGHT.

Witnesses:

GEO. A. BYRNE,
ANNA V. DOYLE.

It is hereby certified that in Letters Patent No. 1,245,144, granted October 30, 1917, upon the application of Herbert L. Bright, of New York, N. Y., for an improvement in "Type-Writer Attachments," an error appears in the printed specification requiring correction as follows: Page 2, lines 101-102, claim 6, strike out the words "as and for the purpose set forth"; and that the said Letters Patent should be read with this correction therein that the same may conform to the record of the case in the Patent Office.

Signed and sealed this 5th day of February, A. D., 1918.
